ELECTRIC UTENSIL CONTROL PLUG

Ralph J. T. Bauer, Briar Cliff Manor, N. Y., assignor to
Casco Products Corporation, Bridgeport, Conn., a cor-
poration of Connecticut

Application January 18, 1957, Serial No. 44,529

Term of patent 7 years

(Cl. D81—25)

Fig. 2

Fig. 5

Fig. 3

Fig. 6

Fig. 4

Fig. 1 is a perspective view of an electric utensil control plug showing my new design;

Fig. 2 is a side elevation of the plug;

Fig. 3 is a plan view of the plug;

Fig. 4 is a side elevation of the other side of the plug.

Fig. 5 is a front perspective view of the control plug.

Fig. 6 is a rear elevation of the plug.

The dotted line showing in Fig. 1 is for illustrative purposes only.

I claim:

The ornamental design for an electric utensil control plug, as shown and described.
